G. E. DIX

HEATING APPARATUS

Filed Jan. 3, 1920

INVENTOR.
George E. Six
BY J. Wilson,
ATTORNEY.

UNITED STATES PATENT OFFICE.

GEORGE E. DIX, OF DURAND, ILLINOIS.

HEATING APPARATUS.

Application filed January 3, 1920. Serial No. 349,205.

To all whom it may concern:

Be it known that I, GEORGE E. DIX, a citizen of the United States, residing at Durand, in the county of Winnebago and State of Illinois, have invented certain new and useful Improvements in Heating Apparatus, of which the following is a specification.

This invention pertains in general to heating systems, and has more particular reference to one in which the circulating air is heated from a source within the room.

The primary object of the present invention is to provide a simple and novel heating apparatus adapted for heating any room having a source of heat, such for example as a stove or a heat-conducting pipe. I propose to heat the air by said source of heat and circulate such air through the room in such manner as to secure even heat distribution and circulation throughout the room, and to obtain this result at no extra cost except that of the simple apparatus employed.

Another object of my invention is to provide a heating attachment adapted to be applied at very little cost to any stove or heater for the purpose of enabling more thorough and economical heating of a room.

I have also aimed to provide an air heating and circulating attachment constructed in such simple manner as to enable production thereof as a commercial article at comparatively little cost.

Other objects and attendant advantages will be appreciated as the invention becomes better understood by reference to the following description when considered in connection with the accompanying drawings, in which—

Figure 1 is a side elevation of a stove equipped with apparatus illustrating the use of my improvements; and

Fig. 2, a front view of the inlet end of the air conduit employed in said apparatus.

In the present invention, I propose to utilize heat from some source such as a stove or any heat conducting pipe, for the purpose of inducing an air current and circulation within a room and for heating such air current so as to obtain greater heating efficiency than would be otherwise possible. One illustration of my improvements is its application to an ordinary stove or heater. In this instance, the heat-conducting pipe in the room to be heated, is the stove pipe or flue outlet through which, as is well

known, a considerable amount of heat is lost because of the inefficient fuel combustion in the ordinary stove.

In the example mentioned, the flue outlet 3 is provided with an enlarged section 4 having an opening 5 near the lower end and an opening 6 near the top. These openings are joined by a conduit 7, and a continuation 8 of said conduit reaches to the lower portion 65 of the room and is equipped with an inlet hood designated generally by character 9. This hood is preferably shaped so as to set against a wall and occupy but little space and is further shaped to provide a relatively 70 wide intake opening 10 through which air may be drawn into the conduit 8. I prefer to employ a screen 11 covering the opening 10 for the purpose of obstructing dust and other foreign matter. This screen may be 75 removed endwise through the opening 12 for the purpose of cleaning. It will be observed that a structure of the character described is adapted to be readily attached to practically any stove or heater, the conduit 8 and hood 80 9 being disposed and arranged in each instance to suit the particular conditions at hand.

By reason of the foregoing construction, the air in the conduit 7 will be heated and 85 upon rising and passing out into the room through the opening 6, will induce an upward current through the conduit 8. The cold air entering the intake hood 9 from the bottom of the room will rise rapidly 90 through the conduit, become heated, and be distributed laterally over the upper portion of the room. Thus, heated air is circulated to practically all portions of the room, where otherwise the air in the room is heated 95 mainly by radiation from the stove. In this manner, greater efficiency is obtained, and likewise economy in fuel, since to heat a given room to a given temperature with the use of my improvements, less fuel is required.

It will be observed that the apparatus employed is exceptionally simple and may be produced at comparatively small cost and sold as an attachment for use with any stove 100 or heater.

My invention also contemplates arranging the conduit 7—8 in co-operation with any heat-conveying pipe in a room so that the air in such conduit will be heated and a current induced so as to cause a circulation such as described above.

It is believed that the foregoing conveys a clear understanding of the objects prefaced above and of the principles involved, and while I have illustrated and described but a single working embodiment of my invention, it should be understood that the same might be embodied in various forms and arrangements without departing from the spirit and scope of the invention as expressed in the appended claim, in which—

I claim:

Apparatus for heating a room, comprising

in combination with a stove in the room having an enlarged flue outlet, an air intake hood adapted to be supported close to the floor and having a back wall and a front wall which diverge upwardly and side walls which converge upwardly, the front wall having an air inlet therethrough, and a pipe connected to the upper end of said air intake hood and passing lengthwise through said enlarged flue outlet and having an air outlet end opening into the room.

GEORGE E. DIX.
